US00D708250S

(12) **United States Design Patent**
Park et al.

(10) **Patent No.:** US D708,250 S
(45) **Date of Patent:** ** Jul. 1, 2014

(54) **PROJECTOR**

(75) Inventors: **Hyoung-Shin Park**, Seoul (KR);
Dong-Kyun Kim, Seoul (KR)

(73) Assignee: **Samsung Electronics Co., Ltd.**,
Suwon-si (KR)

(**) Term: **14 Years**

(21) Appl. No.: **29/426,479**

(22) Filed: **Jul. 6, 2012**

(30) **Foreign Application Priority Data**

Jan. 6, 2012 (KR) 30-2012-0000956

(51) **LOC (10) Cl.** **16-02**

(52) **U.S. Cl.**
USPC **D16/230**

(58) **Field of Classification Search**

USPC D16/200-202, 205, 208, 221, 225,
D16/230-231, 234; D21/514; D14/341,
D14/426, 128, 374; 353/39, 115, 119, 122
